CONDIMENT RECEPTACLE

Filed Feb. 25, 1928

INVENTOR,
1^h William W. Harris,
BY
Henry J. Lucke,
ATTORNEY.

UNITED STATES PATENT OFFICE

WILLIAM W. HARRIS, OF BROCKTON, MASSACHUSETTS, ASSIGNOR TO KETCHAM & McDougall, INC., A CORPORATION OF NEW YORK

CONDIMENT RECEPTACLE

Application filed February 25, 1928. Serial No. 256,857.

This invention relates to condiment receptacles.

An object of the invention is to provide a receptacle in which the condiment is completely sealed against atmospheric attack at all times except at the moment of delivery and having means to effect the intermittent delivery of condiment in desired quantity without agitation of the body of condiment 10 beyond a gradual gravitation equivalent to the amount of discharges and without any intake of air except at the point of delivery and that in amounts only equal to the volume of discharged condiment.

15 The effect of such arrangement is to prevent deterioration in strength of the condiment, which occurs through atmospheric circulation in ordinary receptacles, and to exclude atmospheric vapors to the extent that 20 the condiment is constantly kept in a normally dry and freely deliverable condition. That such objects of the invention have been attained will become apparent when it is 25 fully understood that the total intake of air throughout the intermittent delivery of the entire condiment charge is only equal in volume to the volume of said charge and that the loss of strength through impregnation of such volume of air is infinitesimal and also 30 that no degree of humidity carries sufficient moisture in such volume of air to appreciably affect the body of condiment at any stage of its use.

Another object of the invention is to provide 35 a receptacle having a multiple of condiment chambers and delivery means associated therewith whereby the individual may have more than one condiment in hand, and each immediately deliverable in response to a particular touch of the finger, the said delivery means being also responsive to a single finger touch whereby the simultaneous delivery of a plurality of condiments, in approximately proportionate quantity, is effected. Such arrangement 40 also effects a saving of labor by reducing the number of separate pieces to be handled in table setting and table clearing and also a saving of effort in passing various single receptacles between individuals 45 at the table.

Pursuant to a preferred form of the invention the receptacle is formed with two chambers and provided with selective discharging means adapted to the proper delivery of salt and pepper, the two condiments commonly 55 used in combination.

This double chambered body formation, as made of glass, effects an important economy in manufacture as the accommodation for two condiments is provided by a single glass 60 molding operation.

Further features and objects of the invention will be more fully understood from the following detail description and the accompanying drawings, in which

Fig. 1 is a perspective view of a double condiment receptacle embodying my invention in one form, in use.

Fig. 2 is a side elevation.

Fig. 3 is a top plan.

Fig. 4 is a section at 4—4, Fig. 3.

Fig. 5 is a section at 5—5, Fig. 2.

Fig. 6 is a section at 6—6, Fig. 4.

Fig. 7 is a partial section similar to Fig. 6 inverted.

In the drawings, separate but exactly duplicate parts are designated by the same numeral and referred to as singular in the description.

I have shown the body 1 as made of glass 80 and with two chambers, 1^a and 1^b, having open bottoms but otherwise entirely enclosed. The lower portion of the body 1 is recessed to form the seat 1^c for a yieldable packing element 2 which is clamped to the 85 body by means of the supporting plate 3 and the pivotally mounted spring wire yoke 4, the said yoke co-acting with a cam body formation 1^d to secure the parts under tension and thus hermetically sealing the chambers 1^a and 1^b with the exception of the openings 5 in the yieldable packing element 2 which are located centrally to the respective chambers for the purpose of condiment delivery and charging as hereinafter described. 90 The ends of the yoke 4 are formed inwardly at right angles to establish pivotal connection with the bearing openings 3^a in the downwardly extending flange 3^b of the supporting plate 3. Open spaces 1^e in the base 100

portion of the body 1 are provided to permit the assembly of the respective parts and to further permit freedom of action when the yoke 4 is manipulated to co-act with the cam body formation 1^a. The cam formation 1^a is provided with a slight central depression 1^c for retention of the yoke 4 when positioned therein. The particular formation 4^a of the yoke serves the triple purpose of added resiliency, finger support in assembly manipulation and a thumb and finger support in the use of the receptacle as a whole.

The openings 3^c in the supporting plate 3 are arranged concentric to the delivery openings 5 and are larger in diameter than said delivery openings in order to freely expose the yieldable periphery of the openings 5 to the sealing action of the closure 6. It will be seen that the yieldable packing element 2 serves a dual purpose as the medium for effecting the hermetical sealing of the chamber bottoms and the providing of a yieldable periphery of the delivery openings and thereby acting as a medium for the effective sealing thereof.

The closure 6 is preferably made of yieldable material, such as molded rubber or the like, for the purpose of added compensation, in conjunction with the yieldable periphery 30 of the delivery opening 5, for effecting a reliable seal regardless of the possible interposition of grains of condiment. The closure 6 has an opening 6^a for mounting on the wire arm 7 where it is held in position by frictional contact after being placed in registering location with the delivery opening 5. The arm 7 is hinged to one end of a generally U-shaped carrier frame 8, the other end of which is formed with a catch 8^a adapted to receive the free end of the arm 7. The carrier frame 8 has a secondary U-shaped formation 8^b, extending above the body 1, which serves as the means for finger manipulation and abutment for the spring 9 and also retains the said spring against one angle of lateral movement.

The body 1 is provided with shallow side channels 1^c commencing at completely open spaces 1^h in the base portion and converging at the top portion into a deeper cross channel 1ⁱ, thus forming a retention and guiding means for the carrier frame 8 which is loosely mounted therein to permit of its free reciprocal action in response to either the upwardly exerted spring force or the downwardly applied manual pressure. The side walls of the cross channel 1ⁱ also serve to retain the spring 9 against displacement in the opposed lateral direction.

60 The inwardly extending projection 8^c of the carrier frame 8 is provided to bring the finger pressure area of the two carrier frames sufficiently adjacent to permit of their simultaneous operation by a single finger pressure.

65 Instead of permitting the continuous free

running of condiment upon depression of the closure 6, the preferred construction shown provides a restricting part 10 having a diametrically reduced portion 10^a which is adjustably connected to the closure 6 by the threaded means 10^b, the conformation of the adjacent surfaces, these two parts 6 and 10 being such as to form an annular groove 11 that is preadjustable in vertical dimension for carrying an approximately predetermined amount of condiment upon a single depression of the closure.

The action of the operable parts will be clearly understood from their different positions as shown in Fig. 3 in which the parts 80 in relation with the chamber 1^a are in the normally sealed position and the like parts in relation with the chamber 1^b are shown in the manually depressed position, after having delivered the predetermined amount of 85 condiment.

Again referring to the means employed for effecting a reliable seal of the delivery opening, it will be seen that the lowermost section 5^a of the periphery of the delivery opening 5 is preferably of sharp corner formation as particularly shown in Fig. 6. The reduced portion 6^b of the closure 6 is of approximately the same diametrical area as that of the opening 5. The lower enlarged portion 6^c is of larger diameter than that of the delivery opening 5 and terminates in a tapering formation 6^d which acts as the effective sealing means when retained in tensional contact with the sharp cornered periphery 90 5^a of the delivery opening 5. It will therefore be seen that in the first retractional movement of the closure 6, the reduced portion 6^b serves to free the delivery opening 95 from falling grains of condiment prior to 100 the contact of the actual sealing elements, thus leaving these elements practically free from condiment interference in effecting this important sealing function. The necessity of the intermittent breaking of this seal for 105 the purpose of condiment delivery and the desirability of automatically re-effecting it 110 in a reliable way in order to gain the fullest possible advantage from the otherwise completely enclosed chamber structure, and to accomplish this under spring tension sufficiently light to be easily manipulable, is the reason for designating yieldable material as 115 the preferred means to this end.

The provision for quickly and entirely 120 freeing the delivery opening 5 and thus permitting its use as a charging orifice is most particularly shown in Fig. 6. A slight outward pressure at 8^d springs the free end of the carrier frame 8 from its natural form 125 and permits the escape of the free end of arm 7 so that it may be swung to one side as shown and at the same time effecting the bodily removal of the closure 6 and the restricting part 10, thus fully exposing, for cleansing pur- 130

pose, the only working parts that come into condiment contact. After charging, only the single movement of the arm 7 into engagement with the catch 8^a is required to restore the complete working arrangement. It will be seen that this is all accomplished through simple and positive movements and without any full detachment of parts or any disarrangement whatever of the delivery adjustment. The fact that all other working parts are completely free from condiment contact and are not subject to the otherwise consequent fouling and corrosion, is of particular economical importance as affecting the long life and perfect working of this invention.

While glass, both on account of economy of manufacture and its transparency should be a strongly favored material for the body construction of condiment receptacles, there has been a wide use of other and more expensive materials in the production of the ordinary articles of the kind now in general use. The main reason for this is the difficulty and labor of keeping the walls of the ordinary glass receptacles clear and clean. Only a slight excess of humidity causes condensation on their inner walls with the result that they quickly become coated with either saline deposit or other condiment dust and not only become unsightly but so nearly opaque that they may have to be held against the light in order to discern the amount of condiment content.

The fact that my invention precludes such objectionable conditions and permits the entirely advantageous use of glass body construction is of further economical and labor saving importance.

Whereas I have described my invention by reference to a specific form thereof, it will be understood that many changes and modifications may be made without departing from the spirit of the invention.

I claim:

45 1. A condiment receptacle having a body structure forming a plurality of open bottomed chambers, the walls of said chambers being otherwise entirely closed, means comprising a yieldable element for peripherally sealing said open bottoms, the said peripherical sealing means further comprising a resilient element for maintaining the sealing contact of the said yieldable element under tensional compression, delivery ports in 50 said yieldable element positioned respectively to each of said chambers, closures for sealing the said delivery ports, means exterior of said chambers for supporting said closures and resilient means co-acting with said supporting means for maintaining the said closures in sealing relation with said delivery ports, the said closure supporting means further constituting finger operative means for displacing the said closures within and relative to said delivery ports respectively to

effect the delivery of condiment and also comprising a manually movable member for effecting further displacement of said closures to convert the said delivery ports to charging opening purpose. 70

2. A condiment receptacle having completely closed upper and side wall structure forming a chamber with a bottom opening, means for completely sealing said bottom opening, said means including a yieldable 75 impervious element having a delivery port therethrough and further comprising a tensionally retained closure for said delivery port and finger operative means carried by said receptacle for displacing said tensionally retained closure within and relative to said delivery port to effect the delivery of condiment.

3. A condiment receptacle comprising a condiment receiving chamber provided in 85 one of its sides with an opening, said chamber being otherwise completely sealed, a valve for said opening for controlling the discharge of condiment therethrough, means for operating said valve to effect a movement 90 of said valve outwardly of said opening in the discharge of condiment therethrough, and means for mounting said valve operating means exteriorly on said chamber.

4. A condiment receptacle comprising a 95 condiment receiving chamber provided in one of its sides with an opening, said chamber being otherwise completely sealed, a valve for said opening for controlling the discharge of condiment therethrough, means 100 for operating said valve to effect a movement of said valve outwardly of said opening in the discharge of condiment therethrough, and means for supporting said valve operating means exteriorly on said chamber. 105

5. A condiment receptacle having a discharge opening, closure means for said opening arranged to enter said discharge opening at its closure position, said closure means having spaced enlargements for pre-determining the extent of discharge, means for actuating said closure means outwardly relative to said discharge opening to its discharge position, and means for mounting said closure actuating means exteriorly of 115 said receptacle.

6. A condiment receptacle comprising a condiment receiving chamber provided in one of its sides with a discharge opening, said chamber being otherwise completely 120 sealed, an abutting closure for sealing said discharge opening against entry of atmosphere into the interior of said chamber, means for maintaining said abutting closure in sealing relation with said discharge opening and finger operative means disposed exteriorly of said chamber for effecting a spaced opening between said abutting closure and said discharge opening for the discharge of condiment therethrough. 125 130

7. A condiment receptacle comprising a condiment receiving chamber having completely closed upper and side wall structure, said chamber being provided with a bottom opening, means for sealing said bottom opening, said sealing means comprising a closure member for said bottom opening, supporting means exterior of said chamber for said closure member, means exterior of said chamber for maintaining tensional contact of said closure member against the periphery of said bottom opening, and finger operative means for effecting a spaced opening between said closure member and the periphery of said bottom opening to thereby effect delivery of condiment.

In testimony whereof I have signed this specification this 23rd day of December, 1927.
